pany, Milwaukee, Wis., a corporation of Wis-
consin

Application March 25, 1939, Serial No. 264,148

12 Claims. (Cl. 70—25)

This invention relates to locks, and particularly to permutation padlocks. One object of the invention is to provide a padlock of simple and sturdy construction which shall be thoroughly reliable in operation and adapted for economical manufacture. Another object is to provide mechanism to be actuated for automatically upsetting or disarranging the tumbler permutation as an incident of the movement of the shackle. More specifically, it is an object of the invention to utilize the movement of the longer leg of the shackle for effecting the disarranging of the tumbler permutation, such movement being transmitted to one or more of the tumblers through the medium of intermediate means but without unduly complicating the mechanism. The invention consists in the elements and features of construction in combination, as herein shown and described and as indicated by the claims.

20 In the drawings:

Fig. 1 is a rear view of a permutation padlock embodying this invention, taken substantially as a section at the plane just inside of the back wall of the case to reveal the internal mechanism, and 25 showing the shackle in locked condition.

Fig. 2 is a similar rear view (with an external portion of the shackle broken away) but showing the tumblers adjusted in shackle-releasing position.

30 Fig. 3 is also a rear view showing the shackle partially withdrawn in the initial portion of the unlocking movement.

Fig. 4 is a rear view illustrating a further step in the unlocking movement of the shackle.

35 Fig. 5 is likewise an internal rear view of the mechanism showing the initial part of the closing movement in which the disarranging of the tumbler permutation is accomplished; in this view the shackle-locking lever is shown in section.

40 Fig. 6 is a transverse sectional view taken substantially as indicated at line 6—6 on Fig. 5 to clarify the relative arrangement of the parts in the casing.

Fig. 7 is a detail view of a forked plate carried 45 by the longer leg of the shackle.

Fig. 8 is a detail plan view of the intermediate member by which the shackle accomplishes the disarrangement of the tumblers.

Fig. 9 is an edge view of the member shown in 50 Fig. 8.

Fig. 10 is a face view similar to Fig. 8 showing a modified form of the intermediate member for the same purpose.

Fig. 11 is a sectional view of said modified mem- 55 ber, taken as indicated at line 11—11 on Fig. 10.

and showing in dotted outline the relation of said member to the tumblers.

In the drawings, 15 designates a lock casing which may be of any suitable shape, but which is illustrated as of cylindrical form comprising a 5 front wall 16 and a back plate 17 the front wall being integral with the cylindrical portion of the casing. The casing may be enclosed in a cup-shaped shell 18 preferably of light sheet metal which fits snugly over the casing, and includes a 10 front cover plate 19 disposed against the front wall 16 of the casing. An embossed rear cover plate 20 bears marginally against the back plate 17 and both said plates are secured in place by a flange 21 formed by spinning over the rear 15 edge of the shell 18. Preferably, the front wall 16 and the back plate 17 are further secured together by riveted pins or posts 22 and 23 which may also serve to secure the front cover plate 19 of the shell against the front wall 16 of the 20 casing.

A guide member 25 which may be formed as a sheet metal stamping, is rigidly mounted within the casing and includes a flat portion 26 disposed against the inner surface of the front wall 25 16 and secured thereto by the riveted post 23. Bent up from one end of the member 25 is a flange 27 extending transversely between the front and rear plates 16 and 17 and formed with a round opening 30 in which the shackle 31 is 30 guided.

The legs of the U-shaped shackle 31 extend slidably through openings 32 formed in the cylindrical portions of the casing 15 and shell 18. The longer leg 31^a of the shackle fits slidably and rotatably in the opening 30 in the guide member 25 and the shorter leg 31^b has a beveled end 33 and a locking notch 34 near this end. In the construction illustrated the shackle is free for rotation about the axis of its longer leg when the shorter leg is withdrawn clear of the shell 18, but this freedom for rotation is not essential to the purposes of the present invention. At its inner end the longer leg 31^a of the shackle is formed with an annular groove 38 to receive a forked 40 plate 39 which is retained on the shackle leg by engagement of its straight edge 39^a with the flat inner surface of the back plate 17; this also prevents the plate 39 from rotating about the shackle within the casing, but allows it to travel with the shackle leg whenever the shackle is reciprocated in the casing. The plate 39 also serves to limit the outward movement of the shackle by engaging the guide flange 27 when the shackle is 45 fully withdrawn.

A locking lever 41 is pivotally mounted on the post 22 and carries pocketed within it a spring-pressed latch member shown as a cylindrical plunger 42 slidable in a bore 43 in the locking lever 41 and at right angles to the axis of the post 22. The latch plunger has a beveled nose 44 engageable in the shackle notch 34 to resist withdrawal of the shackle when the parts are at locking position. A coiled spring 45 within the locking lever, urges the latch plunger outwardly while a notch or recess 46 on the side of the plunger adjacent the post 22 provides a stop shoulder engageable with the post, to limit the protrusion of the plunger, as clearly indicated in Fig. 5. An arcuate tongue or lip 47 on the locking lever 41 cooperates with the tumbler means, as hereinafter described.

The stud 48 is rigidly secured, as by riveting, to an embossed portion of the back plate 17 of the casing and projects forwardly through centrally apertured portions of the front wall 16 and the cover plate 19. The tapered front end of the stud 48, as seen in dotted outline in Fig. 6, fits loosely in the bore of an operating knob 50 which is rotatably mounted in the front wall 16. A dished dial plate 51 is carried rigidly on the knob for rotation therewith, and, preferably, the front cover plate 19 of the shell is embossed with an annular bead 54 surrounding the dial. It may be understood that the bead 54 carries an index mark (not shown) and that the dial 51 carries suitable scale markings (not shown), as is customary in permutation locks of this general type.

A driving tumbler or disk 55 is concentrically and rigidly secured to the inner end of the knob and carries the usual transfer lug 56 for cooperation with the other tumblers. Additional tumblers or disks 57 and 58 are shown rotatably carried on the stud 48 with their transfer lugs 60 projecting from adjacent faces for cooperative engagement in the usual manner. The tumblers are separated by washers 61 which are preferably formed to interengage with a key-way 62 in the stud 48 so that they are held against rotation and thus prevented from transmitting any rotative movement from one tumbler to the next. The entire assembly is subjected to limited friction by means of a compressed coil spring 63 surrounding the rear end portion of the stud 48 adjacent the back plate 17.

Each of the tumblers 55, 57 and 58 has a peripheral slot or notch 64 formed to admit the tongue 47 of the locking lever 41, when these slots are registered with each other and with the tongue 47 by adjusting the knob 50 alternately in opposite directions and to successive predetermined positions, the tumblers being thus rotated by predetermined amounts and by interengagement of the lugs 56 and 60 in a well understood manner. Fig. 2 illustrates the tumblers as thus adjusted in registered position.

As soon as the tumblers have been thus registered with their notches 64 opposite the tongue 47 of the lever 41 the shackle can be pulled out; the notch 34 in the shorter leg 31^b of the shackle being interengaged with the end of the plunger 44 will rock the locking lever 41 into the position shown in Fig. 3, in which its tongue 47 is entered in the notches 64 of the tumblers.

Adjacent the rear tumbler 58, the stud 48 carries a rotatable plate 70, and a notch 71 in this plate is engaged by a laterally projecting lug 39^a of the forked plate 39 which is carried by the longer leg 31^a of the shackle. Thus, as the shackle

is withdrawn, the plate 70 is rotated. Instead of being circular like the tumblers the plate 70 has a portion cut away at one side, leaving a straight edge 72 which extends along a chord of the circular outline of the tumblers, but far enough inward to provide clearance for the tongue 47 of the locking lever 41 when the latter enters the tumbler notches, as seen in Fig. 3. As the shackle is pulled farther out and the plate 70 continues to be rotated by the lug 39^a this straight edge 10 72 acts as a cam to engage the tongue 47 and forces it out of the tumbler notches, as shown in Fig. 4. Upon completion of the outward movement of the shackle its shorter leg 31^b is shifted clear of the casing, so that the shackle may be turned freely about the axis of its longer leg 31^a, and, at the same time, the tongue 47 is wholly removed from the tumbler notches. Since this is accomplished by rocking the locking lever 41 about its pivot 22 said lever is thus returned to its normal locking position, ready to receive the shackle when it is thrust back into the casing.

Upon such return movement of the shackle the lug 39^a engaging the notch 71 of the plate 70 25 rotates the plate in reverse direction, and the plate, in turn, engages the adjacent tumbler 58 for shifting its notch 64 out of registration with the tongue 47 of the locking lever, thus upsetting the permutation of the tumblers. And since the 30 tumbler 58 being the last of the series, can only be reset through the agency of the other tumblers which must then be reset, in turn, for registering their notches with the tongue 47 as already described, the upsetting of the tumbler 58 35 insures that the combination must be entirely reset before the lock can again be opened.

In the form shown in Figs. 1 to 9, the plate 70 is provided with a plurality of inclined projections or teeth 73 and the tumbler 58 has a transfer lug 60 projecting from its face adjacent the plate 70 so that as the plate is rotated in the closing movement of the shackle one of its teeth or projections 73 encounters and engages the transfer lug 60 so as to cause the tumbler to 45 rotate with the plate 70 for displacing the tumbler notch 64 from its registered position. The provision of several teeth 73 is desirable, since the transfer lug 60 will be variously located on the tumbler disk in different locks having different 50 "combinations". Only one of the teeth will actually function in any given lock for engagement with the transfer lug.

To insure that the notch 71 of the plate 70 shall remain in position to be re-engaged by the 55 lug 39^a when the lock is again opened, the plate 70 is formed with a radially extending portion which provides a stop shoulder 74 engageable with an opposing shoulder 41^a of the locking lever 41 as seen in Fig. 1. This prevents further rotation of the plate in counter-clockwise direction while the shackle remains closed; rotation in clockwise direction is prevented by the relation of the flaring side 71^a of the notch 71 to the lug 39^a as seen in Fig. 1. When the lock is fully 65 opened a shoulder 75 on the plate 70 encounters the post 23 and thus prevents the notch 71 from being shifted out of range of the lug 39^a. This blocking of rotation of the plate 70 does not interfere with rotation of the tumblers, and particularly the tumbler 58 since the teeth or projections 73 are inclined at both sides, and the plate 70 is urged yieldingly toward the tumbler disk 58 by the spring 63. Thus the yielding of the spring permits the transfer lug 60 to cam 70 75.

itself past the inclined teeth 73 if necessary, when the tumbler is being shifted into position for registering its notch 64 with the other tumbler notches in accordance with the predetermined combination for opening the lock. The spring 63 is sufficiently stiff, however, to insure a driving engagement between the tooth 73 and the lug 60 when the plate 70 is rotated in the closing movement of the shackle for upsetting the tumbler 58.

Figs. 10 and 11 illustrate a modified form of plate 80 which is designed to replace the plate 70 and which engages frictionally instead of positively with the tumbler 58. This plate is formed with a notch 81 for interengagement with the lug 39^a of the plate carried on the longer shackle leg 31^a and its straight edge 82 performs the same function as the edge 72 of the plate 70 in camming the tongue 47 out of the tumbler notches. The plate 80 includes a concentric extension 83 which is offset from the principal portion of the plate so as to provide an inclined shoulder 84 dimensioned to fit against the circular edge of the tumbler disk 58 for frictional engagement therewith. With this construction the tumbler disk is preferably made without a transfer lug 60 projecting toward the plate 80 and there is no positive engagement between the parts. However, the frictional engagement of the plate 80 with the disk 58 is induced by pressure of the spring 63 and is effective throughout the full range of rotation of the plate 80 which is caused by the closing movement of the shackle. For this reason, in most cases the notch 64 of the tumbler disk will be shifted a little farther by the frictionally engaging plate 80 than by the more positive engagement with the tooth 73 of the plate 70.

It will be evident that, if desired, the extension 83 of the plate 80 need not be offset, but may be left in the same plane as the principal portion of the plate, in which event the frictional contact between the face of the plate 80 and the face of the disk 58 will serve for shifting the tumbler. However, this is not always reliable, particularly if one of the two elements should be slightly convex, so that only a small portion of its area could bear frictionally upon the other disk. Therefore, we prefer the dished formation of the plate 80 as shown in Figs. 10 and 11.

While there is shown and described herein certain specific structure embodying the invention, it will be manifest to those skilled in the art that various modifications and re-arrangements of the parts may be made without departing from the spirit and scope of the invention, and that the same is not limited to the particular form herein shown and described, except in so far as indicated by the appended claims.

We claim:

1. A padlock comprising a case having openings, a shackle having legs slidable in said openings, one of said legs being longer than the other, shackle-locking means in said case including a rotatable tumbler movable to release said shackle, and means, rotatable co-axially with said tumbler and yieldably engageable therewith, actuated by the long leg of the shackle in its locking movement to turn said tumbler out of shackle-releasing position.

2. A padlock comprising a case having openings, a shackle having legs slidable in said openings, one of said legs being longer than the other, shackle-locking means in said case including a rotatable tumbler movable to release said shackle,

and a member rotatable co-axially with said tumbler, and so rotated by the long leg of the shackle in its locking movement, together with yielding means urging said member axially into engagement with said tumbler for turning the tumbler out of shackle-releasing position when the member is so rotated.

3. A padlock comprising a case having openings, a shackle having legs slidable in said openings, one of said legs being longer than the other, shackle-locking means in said case including a rotatable tumbler movable to release said shackle, a member rotatable co-axially with said tumbler, and means extending laterally from the longer leg of the shackle and inter-engaging with said member for causing the member to turn when the shackle is moved slidably in the case, stop means for limiting the angle of rotation of said member to keep it within range of engagement by said means on the shackle, and yielding means urging said member axially into engagement with the tumbler whereby its rotation in one direction serves for turning the tumbler out of shackle-releasing position.

4. A padlock comprising a case having openings, a shackle having legs slidable in said openings, one of said legs being longer than the other, a shackle-locking member in said case formed to engage the shorter leg of the shackle for locking it, a plurality of tumbler disks co-axially disposed and having alignable notches to receive a portion of the locking member to permit moving the latter to shackle-releasing position, and a member rotatable co-axially with said tumblers and so rotated by the long leg of the shackle when the latter is moved slidably in the case, said member including a cam adapted to shift the locking member out of the tumbler notches when the member is rotated by the unlocking movement of the shackle and said member being engageable with at least one of the tumblers for turning it out of shackle-releasing position when the member is rotated by the shackle in its locking movement.

5. In a permutation lock, a locking member, a plurality of tumbler disks co-axially disposed and having alignable notches, a shiftably mounted member normally blocking unlocking movement of said locking member except when the notches of the tumblers are adjusted to register with a portion of said shiftable member for permitting such movement, means for adjusting the tumblers in registered relation, and means actuated by the movement of the locking member in frictional driving relation to at least one of the tumblers for shifting it out of registered position when said locking member moves to locking position.

6. In a permutation lock, a locking member, a plurality of tumbler disks having alignable notches, a shiftably mounted member engageable with the locking member for retaining it in locking position and movable to release said locking member when the notches of the tumblers are adjusted in registration to receive a portion of said shiftable member, and a member rotatable coaxially with said tumblers by engagement with the locking member, said rotatable member having a cam portion formed to eject the shiftable member from the tumbler notches when rotated by the unlocking movement of the locking member and being engageable with at least one of the tumblers for turning its notch out of registered position when said rotatable member is

turned reversely by the locking movement of the locking member.

7. In a permutation lock including a case with an opening and a locking member movable therethrough, a shiftably mounted member engageable with the locking member to hold it at locking position, a plurality of co-axially mounted rotatable tumbler disks having alignable notches to receive a portion of said shiftable member when the latter is moved to release the locking member, and means including a plate rotatable co-axially with said tumblers and adjacent one of them, the adjacent faces of said tumbler and plate having mutually engageable projections whereby rotation of the plate serves to rotate the tumbler for shifting its notch out of adjusted position, and means by which the plate is interengaged with the locking member for such rotation when the locking member moves to locking position.

8. A padlock comprising a case having openings, a shackle having legs slideable in said openings, one of said legs being longer than the other, shackle-locking means in said case including a rotatable tumbler movable to release said shackle, and a plate rotatable co-axially with said tumbler and so rotated by the long leg of the shackle in its locking movement, the adjacent faces of said plate and tumbler having mutually engageable projections whereby said rotation of the plate turns the tumbler out of shackle-releasing position, such engagement of the plate and tumbler being maintained by yielding means urging the plate axially toward the tumbler, and one of said said projections being inclined to permit forcing the other past it when the tumbler is rotated independently of the plate in adjusting it to shackle-releasing position.

9. A padlock comprising a case having openings, a shackle having legs slideable in said openings, one of said legs being longer than the other, shackle-locking means in said case including a rotatable tumbler movable to release said shackle, and a plate rotatable co-axially with said tumbler and so rotated by the long leg of the shackle in its locking movement, together with yielding means urging said plate axially into frictional engagement with said tumbler for turning the tumbler out of shackle-releasing position when the plate is so rotated.

10. A padlock comprising a case having openings, a shackle having legs slideable in said openings, one of said legs being longer than the other,

shackle-locking means in said case including a rotatable tumbler movable to release said shackle, and a member rotatable co-axially with said tumbler, the tumbler being circular in outline and said member having a concentric sloping shoulder positioned to engage the circular edge of the tumbler, together with spring means urging said member axially into such engagement with the tumbler, and means on the long leg of the shackle engaging the member for turning it and thus turning the tumbler out of shackle-releasing position when the shackle is moved to locking position. 5

11. In a permutation padlock comprising a case having openings, a shackle having legs slideable in said openings, one of said legs being longer than the other, the shorter leg having a notch, shackle-locking means in said case including a shiftably mounted member engageable with the shackle notch for locking the shackle, 15 a rotatable tumbler having a notch into which said shiftable member is movable to disengage the shackle notch and release the shackle, means rotatable co-axially with said tumbler and actuated by the sliding movement of the long leg 20 of the shackle in the casing, said means including a cam formed to eject said shiftable member from the notch of the tumbler and return said shiftable member to locking position in the unlocking movement of the shackle, and means to 25 engage the tumbler for turning its notch out of shackle-releasing position when said rotatable means is rotated reversely by the locking movement of the shackle, said shiftable member including a yielding portion deppressible by the 30 shorter leg of the shackle and engageable in the notch thereof when the shackle is moved to locking position.

12. In a permutation lock, a locking member, a shiftably mounted member normally blocking 40 unlocking movement of said locking member, locking means in the case including a rotatable tumbler adjustable to release the shiftable member, and a plate rotatable co-axially with said tumbler and so rotated by the locking member 45 in its locking movement, together with yielding means urging said plate axially into frictional engagement with said tumbler for turning the tumbler out of shackle-releasing position when the plate is rotated. 50
